UNITED STATES PATENT OFFICE.

HENRY ALPEN, OF HEMPSTEAD, NEW YORK.

LADDER ATTACHMENT.

1,193,964.

Specification of Letters Patent. Patented Aug. 8, 1916.

Application filed April 14, 1916. Serial No. 91,188.

To all whom it may concern:

Be it known that I, HENRY ALPEN, a citizen of the United States, residing at Hempstead, in the county of Nassau, State of New York, have invented certain new and useful Improvements in Ladder Attachments; and I do hereby declare the following to be a full, clear, and exact description of the invention, such as will enable others skilled in the art to which it appertains to make and use the same.

This invention relates to improvements in ladder attachments.

One object of the invention is to provide a novel and simple device which can be quickly and easily attached to or removed from the stile of a ladder for supporting paint pots, brushes, putty and other articles used by painters.

Another object is to provide a device of this character which includes novel and simple means for detachably and adjustably securing the device to the stile of a ladder, and which will effectively support the articles used by the painter.

Other objects and advantages will be apparent from the following description when taken in connection with the accompanying drawing.

In the drawing: Figure 1 is a front elevation of my device applied to a ladder; Fig. 2 is a top plan view of the device, the side stile of the ladder being shown in section; Fig. 3 is a bottom plan view; Fig. 4 is a longitudinal sectional view on the line 4—4 of Fig. 2; Fig. 5 is an end view of the device; Fig. 6 is a vertical sectional view on the line 6—6 of Fig. 1.

Referring particularly to the accompanying drawing, 10 represents a pan or tray which is provided with a surrounding upturned flange 11 having a rolled and reinforced rim 12. Disposed beneath one end of the pan, and having its upper edge engaging thereagainst is the greater part of a large and strong bowed spring 13. This spring is attached to the underside of the pan, at its intermediate portion by a strap 14, and adjacent one end by a strap 15. Secured to the underside of the pan and straddling the spring adjacent its other end is a strap or stirrup 16, within which that leg or portion of the spring is adapted to be moved. The ends of the spring extend be-

yond the end of the pan in parallel relation, 55 as shown at 17, and secured to each one of these ends is a vertically extending channel member 18. This member 18 is secured intermediate its ends to the end of the spring, and has secured to its outer face a handle 19 60 which straddles the said end of the spring. Secured to the underside of the pan, and extending transversely thereof is a triangular reinforcing strip 20. Struck from the channel members are the inwardly extending tangs or spurs 21 which are adapted to bite into the stile of the ladder 22.

In applying the device to a ladder, the handles 19 are grasped in the hands and the leg of the spring which is loosely disposed within the stirrup strap 16 drawn away from the other leg. This separates the channel members 18 and permits of the ready entrance of the stile of the ladder. When the handles are released, the spring 75 will cause the channel members to firmly engage with the stile of the ladder and drive the spurs into the stile. Thus the device will be firmly held in position to support paint pots, brushes and other tools used by 80 painters, the spring 13 serving as a brace longitudinally of the pan, and the member 20 as a brace transversely of the pan.

After the device has been clamped on the stile of the ladder and it is desired to raise 85 or lower the device, it is only necessary to pull the free end of the spring away from the stile and then slide the device upwardly or downwardly as desired, this whole operation being accomplished with one hand. 90

On each side of the pan or tray 10, and secured to the outer faces of the vertical flanges are the socket members 23, which are adapted to receive the lower ends of the legs 24 of a vertical wire guard 25. This 95 guard will prevent the painter's tools from falling from the tray, especially should the ladder be placed at a great angle with respect to the wall of the building.

What is claimed is:

A shelf attachment for a ladder comprising a tray, a substantially U-shaped spring disposed under one end of the tray and extending beyond the same, means carried by the bottom of the tray for rigidly securing the intermediate portion of the spring and one arm thereof, a guide yoke strap secured to the bottom of the tray and straddling the 105

other arm of the spring, ladder rail engaging jaw members secured to the outwardly extending portions of the spring and provided with tangs for engagement in the rail 5 of the ladder and handles carried by the jaw members for applying and removing the jaws.

In testimony whereof, I affix my signature, in the presence of two witnesses.

HENRY ALPEN.
